[57] CLAIM

The ornamental design for a bottle, as shown and described.

DESCRIPTION

FIG. 1 is a front elevational view of a bottle embodying my new design;

FIG. 2 is a side elevational view thereof;

FIG. 3 is a top plan view thereof; and

FIG. 4 is a bottom plan view thereof.

The back view opposite to that of FIG. 1 is a mirror image of FIG. 1.

The side view opposite to that of FIG. 2 is plain and unornamented.
